(57) **CLAIM**

The ornamental design for a tool holder for grooving machine tool, as shown and described.

DESCRIPTION

1. Tool holder for grooving machine tool

1.1 : Bottom

1.2 : Front

1.3 : Left

1.4 : Perspective

1.5 : Top

1.6 : Back

1.7 : Right

The material is made of metal; the claimed design relates to a tool holder for grooving machine tool which is used for processing the metallic workpiece.
